Frank E. Hutton, Pittsburgh, Pa., assignor to The Babcock & Wilcox Company, Bayonne, N. J., a corporation of New Jersey

Application September 3, 1932; Serial No. 631,846

12 Claims. (Cl. 122—265)

My present invention relates to the construction of fluid heating apparatus embodying spaced groups of straight headers connected by a bank of tubular fluid conduit elements.

4 The general object of my invention is the provision of fluid heating apparatus of the above character with an improved construction and arrangement of the headers and tubes, providing a highly effective arrangement of the heat transfer surface and facilitating the replacement of the tubes. A more specific object is the provision of a high pressure steam boiler of the water tube type with a header and tube construction and arrangement of the above character.

10 The various features of novelty which characterize my invention are pointed out with particularity in the claims annexed to and forming a part of this specification. For a better understanding of the invention, its operating advantages and specific objects attained by its use, reference should be had to the accompanying drawings and descriptive matter in which I have illustrated and described preferred embodiments of my invention.

15 Of the drawings:

Fig. 1 is a sectional elevation through a steam boiler constructed in accordance with my invention;

Fig. 2 is a partial section on the line 2—2 of Fig. 1, illustrating one row of tubes;

Fig. 3 is a fragmentary view on an enlarged scale, showing the tubes joined to the header;

Fig. 4 is a section on the line 4—4 of Fig. 3;

Fig. 5 is a section on the line 5—5 of Fig. 1; and

Fig. 6 is a fragmentary view similar to Fig. 1 illustrating a modification.

The invention is illustrated as embodied in a steam boiler of the water tube type comprising a combustion chamber 10, in which fuel is burned.

40 The fuel burning apparatus may be of any suitable design, and inasmuch as the invention is particularly adapted for use with steam boilers utilizing pulverized coal or other slag burning fuel, fuel burner nozzles 11 are conventionally illustrated. The combustion chamber walls preferably include rows of water tubes 12, in which steam is generated and conducted into the circulating system of the boiler by suitable connections (not shown).

45 Disposed above the combustion chamber is a boiler structure comprising a transversely arranged horizontal steam and water drum 13 connected by nipples 14 to a group of down-take headers 15, and by circulators 16 to a group of

uptake headers 17 arranged at the opposite end of the boiler. As shown in Fig. 1, the down-take headers are vertical, while the uptake headers are at a higher level and inclined at an angle of approximately 45° towards the down-take headers. The groups of headers aid in defining opposite walls of a tapering gas pass through which flow heating gases from the combustion chamber 10 to the outlet flue 20. The headers 15 and 17 are preferably straight headers of substantially circular cross-section, arranged as hereinafter described. The groups of headers are connected by an inclined bank of steam generating tubes 30, arranged in rows across the width of the boiler, with the tubes in each row for a major portion 60 of their lengths concentrically curved relative to the tubes in the remaining rows. The ends of each tube are bent in a predetermined manner and expanded into corresponding uptake and down-take headers, as hereinafter described.

65 Above the tube bank is arranged a superheater having a group of return bend tubes 21 connected to inlet and outlet headers 22 and 23, respectively. The superheater is supplied with steam from the drum 13 through connections 19. The superheater tubes are supported at one end by a wall resting on the tubes 30, the space between the bottom of this wall and the headers 15 being sealed by a baffle 25. The opposite end portions of the superheater tubes are supported in any suitable manner, such as by lugs 26 engaging lugs 27 on certain headers 17.

70 In accordance with my invention, the tubes 30 and headers 15 and 17 are so formed and arranged that the tubes in each row for a major portion 75 of their lengths are substantially uniformly spaced apart to provide gas passages of substantially uniform width throughout the width of the boiler, and which arrangement permits rapid and easy replacement of any of the tubes.

75 As shown in Figs. 1—5, the tubes and headers are arranged in a plurality of side-by-side sections, each section consisting of aligned uptake and down-take headers connected by a group of tubes 30 arranged in pairs spaced longitudinally 80 of the headers. Each pair includes tubes 31 and 32 disposed on arcs of corresponding concentric circles, each tube 31 being disposed nearer the plane passing through the longitudinal axes of the headers in that section than the tube 32 of the pair, and having its end portions equally bent laterally in the same direction to a lesser extent than those of the tube 32. The tubes 30 including their bent end portions may be considered as positioned on the surfaces of concen- 85

tric cylinders. The headers being preferably of circular cross-section, the amount of bending of the tubes 31 and 32 is preferably sufficient to provide a radial entrance of the tubes into the headers. A highly effective arrangement of the heat transfer surface is effected by staggering the tube openings in the headers and by forming the tubes 31' and 32' in the adjacent pairs with end portions similar to the tubes 31 and 32, respectively, and arranging the tubes 31' and 32' at opposite sides of the plane containing the header axes from the tubes 31 and 32, respectively, and turned end-for-end relative to said tubes. A tube sieve will be thus formed in which the tubes in each row are substantially uniformly spaced across the boiler for a major portion of their lengths, providing gas passages of equal width, and the tubes in each row staggered relative to the tubes in adjacent rows, as shown in Figs. 3-5.

In the tube bank shown, the five upper rows are substantially equally spaced apart. Alternate tube rows are omitted in the remaining part of the bank to provide a slag screen in which the tube rows are spaced twice as far apart as the rows in the upper section.

The curving of the major portion of each tube in a vertical plane and the bending of its end portions in a curved plane normal thereto to provide the desirable radial entry into the headers and the effective tube sieve shown would render tube replacement extremely difficult if the headers at each end were arranged as usual with their longitudinal axes in the same plane and if the described tube spacing and proper header ligament strength were desired to be maintained without undesirably increasing the width of the boiler. The necessary amount of header clearance is obtained in the present construction by staggering the headers at both ends of the tube bank, so that the axes of adjacent headers lie in parallel planes. The amount of offset between adjacent headers is made sufficient to provide a clearance between adjacent headers equal to at least a tube diameter and preferably the same at both ends of the tube bank, so that while the tubes vary in length according to their position lengthwise of the headers, for any corresponding position thereon the tubes 31 or 32 will be of equal length in all sections.

In removing any of the tubes 31 and 32, the end portions of the tube are cut loose from the header and the tube manipulated through the successive positions A, B, and C, indicated in dotted lines in Fig. 2. Preferably, the tubes 31 and 32' are removed through an interheader space at the uptake end of the bank, and the tubes 32 and 31' through an interheater space at the downtime end. In positioning a new tube for any tube removed, the nipples are removed from the corresponding tube openings in the headers and the new tube swung over until its far end is seated in the proper tube opening. The tube is then moved longitudinally into that header a sufficient distance to allow its near end to clear the adjacent header. The near end is then inserted in the proper tube opening and the tube ends expanded in the usual manner.

In Fig. 6, my improved tube arrangement is illustrated with the tubes 30^a straight for a major portion of their lengths and both the headers 15^a and 17^a vertical. The tube end portions are bent and the headers staggered as in the embodiment illustrated in Figs. 1-5.

While in accordance with the provisions of the statutes I have illustrated and described herein

the best forms of my invention now known to me, those skilled in the art will understand that changes may be made in the form of the constructions disclosed without departing from the spirit of the invention covered by my claims, and that certain features of my invention may sometimes be used to advantage without a corresponding use of other features.

I claim:

1. Fluid heating apparatus comprising spaced groups of straight headers, the headers in each group being correspondingly staggered and spaced apart a distance equal to at least a tube diameter and aligned with the headers in the other group, a bank of fluid conduit tubes connecting said groups of headers in a plurality of side-by-side sections, each section including a header at each end of said bank and tubes spaced longitudinally of said headers, said tubes being arranged in rows across the width of said apparatus, and each of said tubes having laterally bent end portions and being arranged for removal through an interheader space.

2. Fluid heating apparatus comprising spaced groups of straight headers of substantially circular cross-section, the headers in each group being correspondingly staggered and spaced apart a distance equal to at least a tube diameter and aligned with the headers in the other group, a bank of fluid conduit tubes connecting said groups of headers in a plurality of similar side-by-side sections, each including a header at each end of said bank and tubes arranged in pairs spaced longitudinally of said headers, said pairs of tubes being arranged in rows across the width of said apparatus, and each of said tubes having laterally bent end portions and being arranged for removal through an inter-header space.

3. Fluid heating apparatus comprising spaced groups of straight headers of substantially circular cross-section, the headers in each group being correspondingly staggered and spaced apart a distance equal to at least a tube diameter and aligned with the headers in the other group, a bank of curved fluid conduit tubes connecting said groups of headers in a plurality of side-by-side sections, each including a header at each end of said bank and tubes arranged in pairs spaced longitudinally of said headers, said pairs of tubes being arranged in rows across the width of said apparatus with all of the tubes in each row spaced substantially uniformly for a major portion of their lengths, and each of said tubes having end portions bent out of its plane of curvature and being arranged for removal through an inter-header space at one end of said bank.

4. Fluid heating apparatus comprising spaced groups of straight headers of substantially circular cross-section, the headers in each group being correspondingly staggered and spaced apart a distance equal to at least a tube diameter and aligned with the headers in the other group, a bank of concentrically curved fluid conduit tubes connecting said groups of headers in a plurality of side-by-side sections, each including a header at each end of said bank and tubes arranged in pairs spaced longitudinally of said headers, said pairs of tubes being arranged in rows across the width of said apparatus with all of the tubes in each row spaced substantially uniformly for a major portion of their lengths, one tube of each pair being disposed for a major portion of its length nearer than the other to a plane passing through the longitudinal axis of the header, and each of said tubes having end portions similarly

- bent out of its plane of curvature and being arranged for removal through an inter-header space at one end of said bank.
5. Fluid heating apparatus comprising spaced groups of straight headers of substantially circular cross-section, the headers in each group being correspondingly staggered and spaced apart a distance equal to at least a tube diameter and aligned with the headers in the other group, a bank of concentrically curved fluid conduit tubes connecting said groups of headers in a plurality of side-by-side sections, each including a header at each end of said bank and tubes arranged in pairs spaced longitudinally of said headers, said 10 pairs of tubes being arranged in staggered rows across the width of said apparatus with all of the tubes in each row spaced substantially uniformly for a major portion of their lengths, and each of said tubes having end portions bent out of its 15 plane of curvature, the tubes in adjacent pairs having similarly bent end portions but oppositely arranged and turned end for end, and all of the tubes being arranged for removal through inter-header spaces at the end of said bank.
- 20 6. A water tube steam boiler comprising a combustion chamber, spaced groups of straight headers of substantially circular cross-section, the headers in each group being correspondingly staggered and spaced apart a distance equal to at least a tube diameter and in alignment with the headers in the other group, a bank of curved tubes arranged in rows above said combustion chamber, the tubes connected to each header being arranged in pairs spaced apart longitudinally of 25 said header and having laterally bent end portions, and the tubes forming each pair being arranged for removal through inter-header spaces.
7. A water tube steam boiler comprising a combustion chamber, spaced groups of straight headers of substantially circular cross-section, the headers in each group being correspondingly staggered and spaced apart a distance equal to at least a tube diameter and in alignment with the 30 headers in the other group, a bank of continuously curved tubes arranged in rows above said combustion chamber, the tubes connected to each header being arranged in pairs spaced apart longitudinally of said header and having laterally bent end portions, the tubes in each tube row being substantially uniformly spaced apart for a major portion of their lengths, and the tubes forming each pair being arranged for removal through inter-header spaces.
- 35 8. A water tube steam boiler comprising a combustion chamber, spaced groups of straight headers of substantially circular cross-section arranged to define opposite sides of a pass for heating gases leaving said combustion chamber, the headers in each group being correspondingly staggered and spaced apart a distance equal to at least a tube diameter and in alignment with the headers in the other group, a bank of concentrically curved tubes arranged in rows extending across said gas pass, the tubes connected to each header being arranged in pairs spaced apart longitudinally of said header, each tube having similar laterally bent end portions and one tube of each pair being disposed for a major portion of its length nearer than the other to a plane passing through the longitudinal axes of the headers, the tubes in each tube row being substantially uniformly spaced apart for a major portion of their lengths, and the tubes forming each pair being arranged for removal through inter-header spaces at the sides of said gas pass.
- 40 9. A water tube steam boiler comprising a combustion chamber, spaced groups of straight headers of substantially circular cross-section, the headers in each group being correspondingly staggered and spaced apart a distance equal to at least a tube diameter and in alignment with the headers in the other group, a bank of fluid conduit tubes connecting said groups of headers in a plurality of side-by-side sections, each section including a header at each end of said bank and tubes spaced longitudinally of said headers, said tubes being arranged in rows across the width of said apparatus, and each of said tubes having laterally bent end portions and being arranged for removal through an interheader space.
- 45 10. A water tube steam boiler comprising a combustion chamber, spaced groups of straight headers of substantially circular cross-section arranged to define opposite sides of a pass for heating gases leaving said combustion chamber, the headers in each group being correspondingly staggered and spaced apart a distance equal to at least a tube diameter and in alignment with the headers in the other group, a bank of concentrically curved tubes arranged in rows extending across said gas pass, the tubes connected to each header being arranged in pairs spaced apart longitudinally of said header, each tube having similar laterally bent end portions and one tube of each pair being disposed for a major portion of its length nearer than the other to a plane passing through the longitudinal axes of the headers, the tubes in each tube row being substantially uniformly spaced apart for a major portion of their lengths, and the tubes forming each pair being arranged for removal through inter-header spaces at the sides of said gas pass.
- 50 11. Fluid heating apparatus comprising spaced groups of straight headers, the headers in at least one of said groups being staggered and spaced apart a distance equal to at least a tube diameter and substantially in alignment with the headers in the other group, a bank of fluid conduit tubes connecting said groups of headers in a plurality of side-by-side sections, each section including a header at each end of said bank and tubes spaced longitudinally of said headers, said tubes being arranged in rows across the width of said apparatus, and each of said tubes having laterally bent end portions and being arranged for removal through an interheader space.
- 55 12. Fluid heating apparatus comprising spaced groups of straight headers, the headers in each group being staggered and spaced apart at a distance equal to at least a tube diameter, a bank of fluid conduit tubes connecting said groups of headers in a plurality of side-by-side sections, each section including a header at each end of said bank and tubes spaced longitudinally of said headers, said tubes being arranged in rows across the width of said apparatus, and each of said tubes having laterally bent end portions and being arranged for removal through an interheader space.

9. A water tube steam boiler comprising a com-
